SHOULDER GUN OF RECOILLESS TYPE

Maurice E. Barker, United States Army

Application December 5, 1945, Serial No. 633,029

6 Claims. (Cl. 89—1.7)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates generally, to guns adapted to be fired with the butt of the stock resting against the front of the shoulder after the conventional manner of firing rifles and shotguns, and it has particular relation to such weapons wherein they are provided with gas take-off means permitting the use of propellant charges substantially greater than can now be used with this type of weapon. The gas take-off means reduces the recoil so that it is no greater than that ordinarily encountered with shotguns and rifles.

During the present war there have been a number of developments directed toward providing recoilless weapons enabling the infantryman to carry his own artillery. In general, these weapons have taken the form of an elongated, light weight tube provided with a gas discharge nozzle on the rear end. The principle involved is to have the discharge nozzle so shaped and proportioned that when the weapon is fired the propellant force is counter-balanced, making the weapon substantially recoilless. An example of this type of weapon is the so-called "bazooka." Another example is the 75-mm. recoilless cannon which has recently been given publicity in the newspapers and magazines.

As stated, these recoilless type weapons have provided the infantryman with a weapon for firing a projectile of a size conventionally considered to be fired from artillery weapons. However, despite the success and satisfactory performance of these recoilless weapons, they have certain disadvantages. One of the more important disadvantages is that the recoil blast is of such magnitude that the discharge nozzle must be well back of the soldier using the weapon. Accordingly, these recoilless weapons are ordinarily fired by electrical means with the barrel extending over the shoulder of the soldier in a front and rear direction. Thus, the method of firing is unconventional, awkward, and different from the conventional manner of firing shotguns and rifles with which most soldiers are thoroughly experienced and accustomed to.

Accordingly, the object of this invention is to provide a shoulder type, recoilless weapon adapted to be fired after the conventional manner of firing rifles and shotguns, but having a capacity for much greater propellant charges than can be used in shotguns and rifles, this greater propellant capacity being possible by reason of the pro-

2

vision of a recoilless attachment to the weapon.

For a more complete understanding of the nature and scope of this invention, reference may be had to the following detailed description thereof taken in connection with the accompanying drawings, wherein:

Fig. 1 is a side elevational view of a recoilless weapon forming one embodiment of my invention, with the recoilless attachment removed;

Fig. 2 is a fragmentary top plan view of the weapon shown in Fig. 1 with the recoilless attachment secured in place;

Fig. 3 is a longitudinal section through the elbow section of the recoilless attachment, taken on line 3—3 of Fig. 4;

Fig. 4 is a right end elevational view of the elbow section as shown in Fig. 3;

Fig. 5 is a bottom plan view of the bottom end of the elbow section as shown in Fig. 3;

Fig. 6 is a sectional view of the cartridge chamber of the weapon taken on line 6—6 of Fig. 1;

Fig. 7 is a fragmentary top plan view of a modified form of the invention;

Fig. 8 is a partial vertical sectional view taken on line 8—8 of Fig. 7; and

Fig. 9 is a side elevational view of a cartridge casing adapted for use in the weapon shown in Figs. 7 and 8.

Referring to the drawings, a weapon is shown generally at 10 in Figs. 1 and 2 which is basically a standard 12-gage shotgun modified in accordance with the present invention. The gun 10 is of the type which "breaks" at the line 11 and pivots around a pin 12 so as to open up the breech end of the barrel 13, permitting a cartridge to be inserted in the cartridge chamber 14. The barrel 13 is held closed in the position shown in Fig. 1 by means of a locking lever 15. The muzzle end of the barrel 13 is reinforced with a plurality of rings 16 so as to enable it to withstand greater gas pressures. The trigger mechanism for firing the weapon 10 is that of the conventional, single barrel shotgun.

In order to enable much greater propellant charges to be used in the weapon 10 than can be used with the ordinary shotgun, without increasing the recoil shock, a gas take-off, indicated generally at 20, Fig. 2, is provided. The gas take-off 20 comprises an elbow section 21 (shown in detail in Figs. 3, 4 and 5), a tubular section 22, and a Venturi-shaped nozzle 23 secured on the end of the tubular section 22.

As shown in Figs. 1 and 6, an exhaust opening 25 is formed in the side of the cartridge chamber 14, the breech end of the barrel 13 being built

up on this side so as to permit a flat wall 26 to be machined around the discharge opening 25, which may be tapped in a number of places 27.

The inlet end of the elbow section 21 is shaped correspondingly to the ignition chamber exhaust opening 25 so that it may be securely connected thereto in gas-tight relationship by a plurality of bolts 30, as shown in Fig. 2. The elbow section 21 is strengthened by webs 31 and 32.

The length of the tubular section 22 is such that when the weapon 10 is held in the conventional position for aiming and firing, the nozzle 23 will be positioned over and to the rear of the upper arm or shoulder of the person firing the weapon.

The weapon 10 is particularly adapted to fire the standard rifle grenade provided with a standard impact fuse. This is now fired from rifles with the butts resting on the ground for support. One form of cartridge container used with the new weapon was in the form of a long, perforated brass cylinder containing a large propellant charge similar to that used in the 57-mm. recoilless rifle. The grenade to be fired may be designed to contain one pint of liquid filling of a density about equal to that of water or it may be filled with an equal quantity of white phosphorus or with a hollow charge type HE (high explosive) filling.

An improved modification of the invention is shown in Figs. 7, 8, and 9. Referring to Figs. 7 and 8, a weapon is shown generally at 35 comprising a barrel 36 and a gas take-off 37. The breech end of the barrel 36 is perforated so as to form a shell chamber 38 having a plurality of blast holes 40. The end of the chamber 38 is counterbored at 41 so as to form a recess for the flange 42 of the perforated shell 43 shown in Fig. 9. The shell 43 is preferably formed of brass and has perforations 44 arranged to coincide with perforations 40 of chamber 38. However, the perforations 44 are preferably slightly larger than perforations 40.

In order to insure the proper alignment of the perforations of shell 43 with perforations 40 of chamber 38, a key 54 is provided on the shell 43 and a corresponding recess or notch 45 is formed in the end of chamber 38.

The gas take-off 37 is in the form of an elbow section 50 and a tubular section 51. A discharge nozzle 52 is secured on the end of tube 51. The elbow section 50 at one end surrounds and is spaced apart from the chamber 38 in a gas tight manner being preferably welded thereto as indicated at 55 and at the other end joins the tube 51, as shown. The shape and size of elbow section 50 is such as to provide a sleeve-shaped chamber 53 around chamber 38. The elbow section 50 is secured to the gun barrel around the chamber 38 in a gas tight manner and preferably welded thereto as indicated at 56 in the drawings.

Weapon 35 shown in Figs. 7 and 8 is easier to manufacture, is more effective, and more satisfactory in operation, than weapon 10 shown in Figs. 1-6. The barrel 36 of weapon 35 is preferably 10-gage in size which makes weapon 35 more powerful than weapon 10. The perforated construction of the barrel chamber 38 and the cartridge 43 permits the blast pressure to be instantaneously equalized in the bore of the gun, as well as in the blast chamber 53.

It will be seen that the new weapon provided by the invention can be aimed and fired in the conventional manner. It is a "one-man weapon" and does not require a crew to serve it. There

are no electrical contacts to get out of order. The weapon is loaded in a simple manner, well known to all soldiers and sportsmen. It is believed that this weapon will find great use in projecting gas, smoke, and high explosives into pillboxes, and cave fortifications. The recoil from this weapon in firing a two-pound projectile to a range of 350 yards, is no greater than that delivered by an ordinary 12-gage shotgun.

Although only two specific embodiments of the invention have been described above and shown in the accompanying drawings, it will be understood that other embodiments and modifications will be apparent to those skilled in the art. Accordingly, the foregoing disclosure of the invention is intended to be illustrative and is not to be construed in a limiting sense.

I claim:

1. A gun of the recoilless type adapted to be fired with the butt of the gun resting against the front of the shoulder of the gunner in the conventional manner of firing rifles and shot guns which comprises in combination a gun stock, a gun barrel rigidly secured to said stock, said barrel having a cartridge receiving chamber in its breech end with an exhaust opening in the side of said chamber, a gas take-off comprising a hollow elbow section having an inlet end portion rigidly secured to the barrel in a gas tight manner and in operative communication with said exhaust opening and being provided with an outlet portion smaller than the inlet end portion, a tubular section joined to said outlet portion of the elbow section, and a discharge nozzle provided on the outlet end of said tubular section, said gas take-off extending laterally and rearwardly from said exhaust opening and the breech of the gun and being so shaped that when the gun is held in the conventional firing position said discharge nozzle will extend back of and over the upper arm of the trigger finger arm.

2. A gun of the recoilless type adapted to be fired with the butt of the gun resting against the front of the shoulder of the gunner in the conventional manner of firing rifles and shot guns which comprises in combination, a single barrel shot gun having a cartridge chamber and being provided with a reinforced muzzle portion, an exhaust opening in said cartridge chamber, a gas take-off rigidly secured to said barrel in a gas tight manner and comprising an elbow section having an inlet end portion operatively connected to said exhaust opening in a gas tight manner and being provided with a smaller outlet opening than said inlet portion and a straight tubular section joined to said outlet opening having a Venturi-nozzle provided on the outlet end of said tubular section, said gas take-off extending laterally and rearwardly from said exhaust opening and said gun barrel and being so shaped that when the gun is held in the conventional firing position said discharge nozzle will extend back of and over the upper arm of the trigger finger arm and serve to reduce the recoil of said gun to such a degree that it can be safely fired without injury to the gun.

3. A gun of the recoilless type adapted to be fired with the butt of the gun resting against the front shoulder of the gunner in the conventional manner of firing rifles and shotguns, which comprises in combination, a gun stock, a gun barrel attached to said stock, and a gas take-off connected with and extending laterally and rearwardly from the side wall of the breech of said

barrel, the discharge end of said gas take-off being clear of a person firing said gun when held in said conventional manner.

4. A gun of the recoilless type adapted to be fired with the butt of the gun resting against the front shoulder of the gunner in the conventional manner of firing rifles and shotguns, which comprises in combination, a gun stock, a gun barrel attached to said stock, said gun barrel having a cartridge receiving chamber in its breech end with an exhaust opening in the side of said chamber, a gas take-off comprising an elbow section having an inlet end shaped correspondingly to said exhaust opening and being provided with a smaller outlet opening than said exhaust opening, a tubular section joined to the outlet opening of the elbow section, and a discharge nozzle provided on the outlet end of said tubular section, and means securing said elbow section of the gas take-off, being operatively connected to said exhaust opening and extending laterally and rearwardly from said breech, to said barrel so as to retain it in gas-tight connection with said exhaust opening in said cartridge chamber, said gas take-off being so shaped that when the gun is held in said conventional firing position said discharge nozzle will extend back of and over the upper arm of the trigger finger arm.

5. A gun of the recoilless type adapted to be fired with the butt of the gun resting against the front shoulder of the gunner in the conventional manner of firing rifles and shotguns, which comprises in combination, a single barrel standard 12-gage shotgun with reinforced muzzle, an elongated exhaust opening in one side of the cartridge chamber of the gun barrel, a gas take-off secured to said barrel comprising an elbow section having an inlet end shaped to fit said exhaust opening and being provided with a smaller outlet opening than said exhaust opening, a straight tubular section joined to said elbow outlet opening, and a Venturi nozzle provided on the outlet end of said tubular section, and means securing said elbow section to said barrel so as to retain it in gas-tight connection with said exhaust opening in said cartridge chamber, said gas take-off being operatively connected to said exhaust opening and extending laterally and rearwardly from said breech and being so shaped

that when the gun is held in said conventional firing position said discharge nozzle will extend back of and over the upper arm of the trigger finger arm and said gas take-off serve to reduce the recoil of said gun to a point where it can safely and comfortably be fired with the butt of the gun resting against the shoulder of the gunner.

6. A gun of the recoilless type adapted to be fired with the butt of the gun resting against the front shoulder of the gunner in the conventional manner of firing rifles and shotguns, which comprises in combination, a gun stock, a gun barrel attached to said stock, and a gas take-off mounted on the breech end of said barrel, said gun barrel being perforated at its breech end so as to form a perforated shell chamber, said gas take-off extending outwardly from said shell chamber and laterally and rearwardly from said breech and comprising an elbow section and a tubular section, said elbow section having an inlet end and an outlet end smaller than its inlet end, said inlet end surrounding said shell chamber in spaced gas tight relationship so as to provide a sleeve-shaped blast chamber, said tubular section being joined at one end to said outlet end of said elbow section and having a discharge nozzle provided on its other end, said gas take-off being so shaped than when said gun is held in said conventional firing position said discharge nozzle will extend back of and over the upper arm of the trigger finger arm.
